UNITED STATES PATENT OFFICE.

GEORGE W. NELSON, OF CLEVELAND, OHIO, ASSIGNOR TO THE STANDARD SEWING
MACHINE COMPANY, OF CLEVELAND, OHIO, A CORPORATION OF OHIO.

BUTTONHOLE-SEWING MACHINE.

1,247,139.

Specification of Letters Patent. Patented Nov. 20, 1917.

Application filed July 19, 1913. Serial No. 779,984.

To all whom it may concern:

Be it known that I, GEORGE W. NELSON, citizen of the United States, and resident of Cleveland, in the county of Cuyahoga and State of Ohio, have invented certain new and useful Improvements in Buttonhole-Sewing Machines, of which the following is a specification.

This invention relates to button-hole machines, the same being an improvement upon the button-hole sewing machines disclosed in my prior Patents Nos. 887,503 of May 12, 1908 and 949,401, of February 15, 1910. The principal objects of my present invention are to provide an improved button-hole sewing machine in which the several movements of the work-clamp are under more perfect control, for the purpose of obtaining an even spacing of the button-hole 20 stitches proper, *i. e.* the short stitches at the sides of the button-hole, and for regulating the number and length of the barring 25 stitches made at each end of the button-hole, regardless of the length of the button-hole or the number of button-hole stitches made 30 to complete it; to provide an improved shifting mechanism for the work-clamp and means for controlling all the operations 35 thereof from a single point in the machine and regulating these movements at will, within limits, without interference with the 40 operation of the main controlling mechanism therefor; and to furnish in connection with the other parts, an automatic stop mechanism, the operation of which is not dependent upon the number of stitches made, but which is operated in a predetermined relation to the cycle of button-hole-forming operations.

Various other features of the invention not hereinbefore referred to will be herein-after described and claimed and are illustrated in the accompanying drawings in which,

Figure 1 is an elevation of a button-hole sewing machine embodying my present invention, the view being taken looking from the right-hand side thereof as viewed from the front or sewing end of the machine;

Fig. 2 is a sectional plan of the same, the section being taken in line 2—2, Fig. 1;

Fig. 3 is an under-side view of the mechanism, mainly that below the main bed-plate of the machine, showing the parts 55 in positions corresponding to those of Fig.

2, that is to say, in position for making barring stitches and just in advance of the automatic stopping of the machine after the completion of a button-hole;

Fig. 4 is an enlarged, vertical, sectional 60 elevation showing the parts when in position for bar-stitching, as in Fig. 3, the section being taken in line 4—4, Fig. 1, looking toward the front or sewing end of the machine, as indicated by the arrows;

Fig. 5 is a similar view looking toward the rear end of the machine, the section being taken in line 5—5, Fig. 1, and showing the parts in positions corresponding to those illustrated in Figs. 3 and 4;

Fig. 6 is an under-side view similar to Fig. 3, of a portion of the machine, and illustrates the parts in position for making the ordinary short or button-hole stitches;

Fig. 7 is an enlarged transverse section 75 and elevation of the same, the section being taken in line 7—7, Fig. 6, looking in the direction of the arrows, and the parts being in the same positions as in Fig. 6;

Fig. 8 is an enlarged detail illustrating 80 in horizontal section and plan various elements of the main operating mechanism for imparting longitudinal and transverse movements to, and controlling these movements of, the work-clamp, the parts being 85 in the same positions as in Fig. 2;

Fig. 9 is an enlarged detail illustrating 90 in horizontal section and plan, with the section taken at a point below the bed-plate of the machine, other portions of the operating mechanism for imparting longitudinal and transverse movements to the work-clamp and for equalizing such longitudinal movements, and also shows means for automatically stopping the machine on the completion of a button-hole, and

Figs. 10 to 13 inclusive are details illustrating in plan and partly in section various positions of the mechanism for imparting longitudinal and transverse movements to the work-clamp and for equalizing such longitudinal movements, Fig. 10 illustrating the last stage in the operation of making the button-hole, *viz.* the making of the second group of barring stitches, while Figs. 11, 12 and 13 illustrate respectively the first, second and third stages in such operation, *sc* to wit, the making of the first or left-hand row of stitches, the making of the first group 110 of barring stitches at the rear end of the

button-hole, and the making of the second row of short or button-hole stitches at the right-hand side of the button-hole.

Similar characters designate like parts in all the figures of the drawings.

Many of the features of the present machine are or may be similar to those of the button-hole sewing machines described in my prior patents before referred to, but as 10 most of the parts have been considerably modified both in structure and in the manner in which they are combined with other parts of the machine, most of these parts will be described in detail.

15 The reference numeral 2 represents a main or fixed base adapted to be attached by suitable means, such as screws, to the top of a sewing machine table or other support, and 3 represents the bed-plate proper of 20 the machine which may be hinged or otherwise connected to the part 2 in any suitable manner, and carries in this case all of the operating parts of the machine. At the front end of the bed-plate 3 there is the usual 25 plate, 4, having therein an elongated opening 5, of the usual form, for permitting the descent of the needle and also, at the proper time, of a knife for cutting the button-hole.

The work is clamped in place, as usual, in 30 a work-clamp, the upper and lower clamp-plates of which are here indicated by 6 and 7. The upper clamp-plate is mounted on an arm that extends both rearwardly and toward the right of the machine, this arm being indicated at 8 and being mounted so as to move both horizontally and vertically, the latter movement being preferably about a horizontal axis. This horizontal axis of the arm 8 is indicated at 9, which shows a 35 pivot-pin mounted in lugs rising from a lateral extension, 10, of the main slide, 11, by which the lower clamp-plate 7 is carried. The main slide 11 for the clamp-plate is mounted to move back and forth on a central fixed plate 12 between suitable guides, such as 13 and 14. Near its center this slide has a projection, 15, rising therefrom to which is pivoted, at 16, a connecting-rod or link, 17, which constitutes the principal 40 means for transmitting longitudinal movement forward or backward to the work-clamp. At its rear end this connecting-rod is pivoted to a crank-disk 18, mounted for rotation on the plate 12 near the rear end 45 thereof, said crank-disk having in the upper surface thereof a diametrical slot, 19. In this slot 19 a pivot-screw, 20, is mounted and may be adjustably secured in place at any desired point in the length of said diametrical slot so as to locate the pivot point either at the center or at any suitable distance (within limits) from the center of said crank-disk, to correspondingly regulate the extent of the longitudinal movements of the slide 11 for making a button-

hole, it being understood that this crank-disk is intended to have a step-by-step movement similar to that set forth in my prior patents aforesaid.

One of the principal features of the present invention is the provision of operating means of an improved type for imparting to the work-clamp short longitudinal step-by-step movements of any desired length within limits. Here these movements are derived from the main upper driving shaft 21 through suitable operating connections, preferably of the type which will now be described. The main drive-shaft 21, mounted in the overhanging arm of the machine, 80 has two eccentric rods 22 and 23, by means of which movement is imparted to a pair of rock-arms movable about horizontal axes. One of these rock-arms is illustrated at 24 and is secured to a short rock-shaft, 25, carried by suitable bearings (here shown as pivot-bearings) supported by lugs, such as 26 and 27, depending from the under side of the bed-plate 3 and integral with the second of a pair of depending ribs or longitudinal flanges, 28 and 29, also integral with said bed-plate. The rock-shaft 25 in turn has an upwardly projecting rock-arm 30 the upper end of which projects through an opening, 31, in the bed-plate into position 85 for operating a transverse slide, 32, by means of which movement is transmitted to the crank-disk 18 to turn the same step-by-step. The slide 32 is mounted to move transversely back and forth across the top of the bed-plate between the side walls of a guide-way indicated at 33. The range of movement of this slide 32 is preferably adjustable, as by means of an adjusting screw, 34, in the upper end of the rock-arm 30, which cooperates with a vertical lug, 35, at the extreme left-hand end of the slide 32, for the purpose of controlling the range of movement of the slide. The movement of the slide to the left is determined by the stop-faces of 100 the parts 34 and 35. The movement to the right is shown as determined by stops, such as 36 and 37, the latter of which is formed by the front end of a block rising from the slide 32 and on which is pivoted, at 38, a 105 lever 39, the forward end of which is in turn pivoted, at 40, to one end of an operating lever or pawl, 41, (see Fig. 8) by means of which motion is imparted step-by-step to the crank-disk. Here the lever 39 has a 110 pair of arms from which springs, such as 42 and 43, extend to suitable fixed stops, the spring 42 serving to move the long arm of the lever 39 toward the crank-disk, while the spring 43 serves to draw the lever 39 and 115 with it the slide 32 back toward the left-hand side of the machine, as seen in Fig. 2. The crank-disk 18 has in this case in the under side thereof as illustrated more particularly in Fig. 8, an annular groove with 120

vertical walls, which annular groove is designated by 44, and the lever 41 connected to the operating lever 39, which lever constitutes an operating pawl and has at its free 5 end a tooth 45, is adapted to coöperate with the walls of the annular groove 44 for the purpose of imparting step-by-step movement to the crank-disk 18. The operating pawl or lever 41 is curved, as is shown in dotted 10 lines in Fig. 8, and is intended to work in a horizontal plane immediately below the under side of the crank-disk 18. The tooth 45 of said pawl extends upwardly and is so shaped that the point, 46, thereof impinges 15 against the inner wall of the groove 44 as does the opposite edge, 47, against the outer wall of said groove, and as the slide 32 is moved toward the right-hand side of the machine (as seen in Figs. 2 and 8) serves 20 to bite said walls and turn the crank-disk a distance corresponding to the movement of the slide. This movement may of course be regulated as desired, though at each step the movement of the pawl will, in the construction shown, always be the same for a given setting of the parts. Obviously, on the return stroke of the slide 32 the tooth 45, turning about the pivot 40 of its pawl, will be released from the walls of the groove 44 25 and will slide freely therein to a position for obtaining a new grip upon the walls of said groove. In addition to the operating pawl and tooth just described, I also prefer to employ a hold-back pawl which may be constructed as illustrated at 48. This hold-back pawl is pivoted at 49, it being slotted or divided at 50 to enable it to pivot about the pin 49 and yet have a slight longitudinal movement radial thereto, and this pawl also 30 has a tooth, 51, similar to the tooth 45 and adapted to grip or pinch the walls of the slot 44 and prevent return movement of the crank-disk. A spring is shown at 52 for normally holding the tooth 51 of this pawl 35 in position for preventing such return movement.

The connections just described from the main drive-shaft through the eccentric-rod 22 and the connections therefrom to the 40 slide 32, the step-by-step movement just described, and the connecting-rod 17, are sufficient for the purpose of imparting to the work-clamp a longitudinal movement representing the distance between the short or 45 button-hole stitches to be made. For the purpose of determining and controlling the length of each individual stitch, whether a short button-hole stitch or a long stitch for forming a bar at the ends of the button-hole, 50 means must of course be provided, as before stated, for shifting said work-clamp sideways and for also determining and controlling the position and extent of these sideways movements. The sidewise movement of 55 the slide 11 carrying the work-clamp will

also preferably be effected from the main drive-shaft 21, the shifting mechanism for the work-clamp differing radically in this respect from the mechanisms of my aforesaid patents. Here the main drive-shaft 21 70 has upon it a spur-gear, 53, which meshes with the teeth of a larger spur-gear, 54, carried by a short shaft, 55, substantially parallel with the shaft 21 and mounted in suitable bearings in brackets, 56, projecting 75 from the arm or upper portion of the main frame of the machine, and covered, as indicated, by a plate 57, for the purpose of forming a casing substantially inclosing said large gear and certain other parts. 80 The shaft 55 also carries a stop-collar or disk, 58, between which and the large spur-gear 54, a cam 59 on the shaft 55 works. (See Figs. 1 and 4). This cam controls the operation of a vertical shifting lever, 60, 85 the movements of which are so timed as to cause the clamp slide 11, through suitable connections, to be moved sidewise once at each operation of the needle, this movement sidewise taking place on the up stroke of the 90 needle. In the preferred construction, a main cross-slide is provided which is operated by the lever 60 and this cross-slide has not only a movement crosswise of the bed-plate but it also has a crosswise movement 95 the extent of which is dependent upon whether short buttonhole stitches or barring stitches are to be made. In addition to this in the present machine there is not only a main cross-slide having such a differential 100 movement, but there is also employed, in connection therewith, an auxiliary cross-slide which moves with the main cross-slide at certain times and at other times moves crosswise of the machine relatively to 105 said main cross-slide. These main and auxiliary cross-slides proper are designated here- 110 in respectively by 62 and 63, the former being mounted to slide transversely in a corresponding transverse guide-way, 64, in the plate 12, while the latter is mounted to slide transversely of the machine in a correspond- 115 ing guide-way in the upper part of the main cross-slide, which guide-way is also disposed transversely of the machine. The auxiliary cross-slide 63 is also located at its 120 opposite ends by guides, 65 and 66, through which it slides, and is operatively connected between its ends to the clamp slide 11 to impart movement thereto by means of a piv- 125 oted block 63' on its under side engaging the clamp slide within a longitudinal slot 11' therein. The vertical shifting lever 60 before described is pivoted directly to this auxiliary slide, as indicated at 67, by means of a pivot-screw passed through said lever and also through a lug, 68, rising from the upper auxiliary slide 63. The extent of movement of the slide 63 transversely of the machine is dependent upon the stroke 130

of the lever 60, and this lever is intended to have a changeable stroke, one stroke of which corresponds to the desired length of the short or button-hole stitches and the other of which corresponds to the longer barring stitches. In order to provide for this variation in the lengths of the stitches made, the fulcrum of the lever is, in this case, shiftable from one to another of two different points in the length of the lever 60, this fulcrum being indicated at 69 and being shiftable from the upper position, shown for example, in Fig. 7, which corresponds to the making of short or button-hole stitches, to the lower position shown in Fig. 4, which corresponds to the making of the longer barring stitches. The difference in movement of the proper cross-slide 63 is controlled by the difference in the distance in the two cases between the fulcrum 69 of the lever 60 and the point 67 at which said lever is pivoted to said slide 63. In addition, however, to this change of leverage there is also provision made for changing the position of the main cross-slide 62 and with it of course that of the auxiliary cross-slide 63 which is directly connected to the lever 60. Said main slide 62, in addition to supporting the auxiliary slide 63 which is operated at each stitch by the lever 60, also has a depending member to which said lever 60 is fulcrumed and which serves to shift said fulcrum, as well as the slide 63 and the point of connection 67 between the lever 60 and the slide 63, from one to another of various positions corresponding respectively to positions for a right-hand button-hole stitch, a left-hand button-hole stitch, and a barring stitch. This depending member, indicated at 70, constitutes a guide, it having a guide-way, 71, in which there is mounted to slide a block, 72, which carries the fulcrum 69 of the lever 60. The fulcrum screw 69 is slideable in this vertical guide-way 71 between the positions shown in Figs. 4 and 7 respectively. At each stroke of the needle the shifting lever 60 moves the cross-slide 63 toward the right or the left of the machine and thereby turns the connecting clamp plate or slide 11 about its fulcrum 11" to impart the necessary sidewise movement to the work-clamp for properly presenting the work to the sewing mechanism in the formation of a button-hole stitch. Whether the terminal points of these stitches are the ends of a right-hand stitch, or a left-hand stitch, or a barring stitch, will depend upon the position of the main slide 62. Of course the positions of the terminal points of each individual stitch will be determined by the position of the cam 59 at the right or left extreme position (see Fig. 4) and also upon the position of the fulcrum 69 vertically (see Figs. 4 and 7).

65 Any suitable means may also be employed

for effecting the shifting movements of the main cross-slide 62 and the fulcrum 69 of the shifting lever 60. Two different mechanisms are employed herein for accomplishing these two results, but both are so controlled as to operate substantially in the same timing. The mechanism here illustrated for controlling the fulcrum-shifting means comprises a long rock-shaft, 74, extending substantially from end to end of the machine and supported, as in the case of the short rock-shaft 25, by pivot-bearings, 75, carried respectively by lugs 76 and 77, at the opposite ends of the machine. This shaft is shown as having thereon a sleeve, 78, mounted to turn on the rock-shaft and carrying a rock-arm, 79, which has a loose connection—preferably a pin-and-slot connection as indicated at 98—with the free end of a long lever, 80, secured to a sleeve, 81, mounted to turn freely on the rock-shaft 25. A strong spring, 82, normally holds the lever 80 up with a lateral ear, 83, in position to coöperate with a pair of substantially semi-circular controlling cams, 84 and 85, carried by and movable in unison with the crank-disk 18 and constituting parts of a rotary-controller adapted for governing various operations of the mechanism. Each of these cams 84 and 85 rises from a low point to a high point, as indicated in Fig. 3, off which high point the ear 83 is adapted to drop under the action of the spring 82 with a quick let-off movement for a purpose to be presently described. The position of this lever 80 serves to control the action of the fulcrum-shifting lever before referred to for raising or lowering the fulcrum 69 of the shifting lever 60. This fulcrum-shifting lever is designated generally by 86. It is shown as secured to a short sleeve, 87, loosely mounted on the rock-shaft 74 between a stop-collar, 88, and the forward end of the sleeve 78, so that the fulcrum-shifting lever is at all times free to turn on said rock-shaft. The sleeve 78 is also shown as having a short rock-arm, 89, projecting radially and laterally therefrom to form a hook adapted to work in the path of said fulcrum-shifting lever 86. A strong coiled spring is also shown at 90 as wound around the long sleeve 78 and as having its rear end connected to said sleeve and its forward end bent to engage the upper side of the fulcrum-shifting lever near the periphery of said sleeve. This fulcrum-shifting lever is bifurcated at its free end to straddle the shank of the fulcrum screw 69, (see Fig. 7) and also has, close to the rear end of such bifurcation, an angular detent, 91, which, when the fulcrum-shifting lever is in its uppermost position, is intended to be held by a latch, such as 92, pivoted on the under side of the plate 12 and normally pressed by a spring, 93, toward said detent 91. At the

70 75 80 85 90 95 100 105 110 115 120 125 130

end opposite that at which this latch 92 engages the angular detent 91 of the fulcrum-shifting lever 86 said latch has an extension, 94, which projects into the path of rotary 5 tripping or let-off means also movable, as are the cams 84 and 85, in unison with the crank-disk 18. This let-off means may be any kind suitable for the purpose and may be adjustable or not as desired, but is preferably adjustable in position for the purpose of determining the point in the length of a button-hole at which the work-clamp will be shifted sidewise for the barring action, etc. Here two adjustable plates, 95-95, 10 are secured, as by means of screws, to the under side of a rotary controller movable in unison with the crank-disk 18, and each of these adjustable plates has a projecting nose or tappet, 97, adapted at a suitable point in 15 the rotation of the controller, 96, to engage the nose 94 of the latch 92 and release said latch from the angular detent 91 of the fulcrum-shifting lever 86, to permit the latter to lower under the influence of the spring 90. Obviously the latch 92 will be released in this case twice during each complete rotation of the crank-disk, once near each end of the button-hole. On each rotation of the 20 upper main drive-shaft 21 movement is imparted through the connections before described step-by-step to the crank-disk 18 and hence to the semi-circular cams 84 and 85 up one of which the ear 83 of the long lever 80 gradually rides swinging with it 25 at the same time about the axis of the shaft 74 the rock-arm 79, the sleeve 78 and the short rock-arm 89. Before the ear 83 reaches the top of either of the cams 84 and 85, however, the spring 90, which is put under tension during the turning of the sleeve 78 has 30 operated to swing the fulcrum-shifting lever 86 downward suddenly to shift the fulcrum 69 to the lowermost position. In other words, during each complete rotation of the 35 rotary controller carrying the semi-circular cams 84 and 85 the fulcrum-shifting lever 86 is shifted twice by the spring 82 to its uppermost position and twice by the spring 90 to its lowermost position, one downward 40 and one upward movement occurring near or at each end of the button-hole. These movements in opposite directions result from the fact that the spring 82 is not in a condition to act at the time when the spring 45 90 is under tension and from the fact that when the spring 82 is released its power is superior to that of the spring 90, the downward movement of the fulcrum-shifting lever being thus assured before the ear 83 50 reaches the top of either semi-circular incline, and the upward movement of such lever being also assured when said ear drops off the top of one incline on to the bottom of the other. Of course, the spring 90, however, 55 will be ineffective to lower the ful-

crum-shifting lever until the release of the detent 91 by the latch 92 and this release will take place some distance in advance of the dropping of the ear 83 off the top of a semi-circular cam, and will be controlled by 70 one of the let-off devices or tappets 97 in a direction circumferentially of the controller 96, provision is of course made for adjustment of the point of release of the detent 91 by the latch 92 relative to the point of release of the lever 80 when the ear 83 leaves the top of either cam 84 or 85. Hence there is provision, through this adjustment, for varying the point at which the fulcrum-shifting lever drops to shift the pivot 69, 75 80 to its lowermost position controlling that throw of the shifting lever 60 which permits the making of the barring stitches at either end of the button-hole. In other words, by shifting either or both of the adjustable let-off devices or tappets 97 the point at which the making of barring stitches at either or both ends of the button-hole begins may be 85 positively determined and hence the number of barring stitches so made at either or 90 both ends of the button-hole may also be determined and varied, as will be evident, within quite wide limits. In the construction shown the point at which the making of the regular or short button-hole stitches begins remains fixed, being determined by 95 the let-off of the ear 83 from the high point of one or the other of the semi-circular cams 84 and 85.

The parts just described are sufficient to 10 determine and control the points at which the shifting lever 60 and other elements of the shifting mechanism for moving the work-clamp sidewise shall operate to shift the work-clamp from a position for making 10 short or button-hole stitches to a position for making long or barring stitches and vice-versa. The means for actually imparting movement to shift said lever 60 and the mechanism connecting it with said work-clamp to the right or to the left of the button-hole will now be described.

The mechanism for actuating the shifting mechanism may be any suitable for the purpose. That shown herein comprises a rotary 115 cam, also preferably movable in unison with the crank-disk 18 and the controller 96, and this rotary cam in the construction shown operates a shifting-bar, 99, having at its front end a long guide slot, 100, adapted to 120 engage a fulcrum-block, 101, carried by a pivot member, 102, adjustably mounted in a longitudinal slot, 103, in the plate 12. The rear end of this shifting-bar is shown as having at its under side an anti-friction 125 roll, 104, adapted to travel in a cam-groove in the upper face of the rotary cam 105 aforesaid. The groove of this cam is shown (see Figs. 9 to 13) as having four main parts, designated respectively by 106, 107, 130

108, and 109. These sections of the cam-groove of cam 105 correspond respectively to the making of short stitches at the left-hand side of the button-hole, the making of barring stitches at the rear end, the making of short stitches at the right-hand side and the making of barring stitches at the front end, as indicated clearly in Figs. 10 to 13 inclusive, the first of which represents the last 10 set of stitches and the last three of which represent the first three sets of stitches made in said series of operations. As the cam 105 rotates it presents the cam-grooves 106, 107, 108 and 109 successively, and the shifting-bar 99 is oscillated by the cam to the successive positions shown in these views. These shifting movements correspond to and effect the lateral shifting of the work-clamp to its four main positions determining 15 the making of the right or left-hand row of button-hole stitches, or the front or rear group of barring stitches.

From the shifting-bar 99 connection is made to the main cross-slide 62 carrying the 20 shifting lever 60 and certain other parts hereinafter referred to controlled by the rotary cam 105. The connecting means employed may also be any suitable for the purpose. In this case I have shown a slide-bar, 110, the free end of which works in a 25 guide, 111, and the other end of which is secured to and constitutes substantially an extension of the main slide 62, while near its center said slide-bar is pivotally secured to 30 the shifting-bar 99, said pivot being indicated at 112. Thus through the connections from the cam 105 by way of the shifting-bar 99, the slide-bar 110, the main cross-slide 62, the shifting lever 60 and the auxiliary 35 cross-slide 63, the main clamp slide 11, which is pivotally connected to said auxiliary cross-slide 63, is shifted at the proper time to any one of the four positions represented by the cam-grooves 106 to 109 inclusive 40 to permit the making of any one of the four sets of stitches used to form a complete button-hole. It will be clear from the foregoing that in each of these four positions the clamp-slide 11 has a crosswise movement 45 that is determined by the swinging of the lever 60, and that this movement will be a swing in a short arc when the pivot 69 is up for making an ordinary short-button-hole stitch, while said lever will swing in a 50 long arc when said pivot 69 is down for making a barring stitch at either end of the button-hole.

Certain of the parts just described also 55 constitute an important improvement upon the equalizing means shown in my aforesaid prior patents for equalizing the longitudinal feed movements of the work-clamp during the making of a button-hole. The principal parts that coöperate in the present case to 60 obtain this result are the crank-disk 18, the

connecting-rod 17, extending from it to the longitudinal clamp-slide 11, the cam 105 rotatable in unison with said crank-disk and the shifting-bar 99 controlled by said cam. By referring again to Figs. 10 to 13 inclusive it will be seen that the connecting rod 17 and the clamp-slide have longitudinal movements of little or greater length according as the point of connection 20 of said rod and the rotary controller is near to or far 70 from the dead center position indicated by the dot-and-dash lines, and that the several principal coöperative parts just referred to are so connected that the minimum feeding movement of the connecting-rod 17 longitudinally, and hence of the work-clamp, will take place when the cam-groove 107 or the cam-groove 109 is in position to coact with the shifting-bar 99, and that the maximum feeding movement of the connecting-rod 17 80 and associated work-clamp takes place when the cam-groove 106 or the cam-groove 108 is in position to coact with the lever 99. By referring to Figs. 10 to 13 inclusive the relation of these parts will be clear. It will be 85 seen that the point of connection of the connecting-rod 17 with the crank-disk 18 is so related to the positions of the cam-grooves 106, 107, 108 and 109 and to the point at which the antifriction-roll of the shifting-bar 99 coöperates with said grooves, that when the point of connection 20 is so positioned that the connecting-rod 17 has but little longitudinal movement the antifriction roll will be in one of the short cam-grooves 107 or 109, as indicated in Figs. 10 and 12, during which period the barring stitches will be made. It will also be seen 90 that when this pivot point 20 is so positioned that said connecting-rod 17 has a 95 considerable movement and is moving toward or from its maximum point, said antifriction roll of the shifting-bar 99 will be in one of the cam-grooves 106 or 108 controlling the making of the short or button-hole stitches. The parts are so related and their movements so proportioned that a substantially equal longitudinal feed movement of the work-clamp in either direction for 100 making short button-hole stitches results. 105 Of course, as before pointed out, the length of each step movement may also be regulated at will within limits, the particular type of step-by-step feed movement employed herein being particularly adapted for 110 permitting fine changes of stroke.

In addition to the parts previously described as operated by the lateral movement of the shifting mechanism for changing the crosswise position of the work-clamp at 115 different periods in the operation of making a button-hole, certain other parts are operated by said shifting mechanism, one of these being a tension-releasing device for releasing the tension on the needle-thread dur 120 125 130

BEST AVAILABLE COP⁷

1,247,180

ing the time that the barring stitches are being made and also upon the completion of the button-hole, and another of which is a shifting device for the lower-thread pull-off, indicated generally by *p*.

The tension device for the needle-thread which is controlled by this lateral movement of the shifting mechanism is indicated at 113 and may be of any suitable type for the purpose. In the present construction its operation is shown as controlled by a longitudinal rod, 114, which is normally pressed toward the rear of the machine by a spring, 115, to permit of the tension being applied to the thread. Near its rear end this rod is supported by and guided in an opening passing through a lug, 116, depending from the neck of the frame-work. At a point between said guide and the spring 115 and relatively near the rear end of the rod 114 connection is made to a suitable operating device controlled by the main cross-slide 62 for releasing the tension device 113 from the thread. These connections may of course be any suitable for the purpose. As here shown they comprise a toggle, 117, pivoted at its ends, at 118 and 119, respectively, to the lug 116 and to a fixed point in the rod 114 and pivoted at 120 at its center to the right-hand end of a link, 121, the opposite end of which is pivoted to the free end of a horizontal rock-arm, 122, secured to the upper end of a vertical rock-shaft, 123, mounted in suitable bearings in the neck of the frame and in the plate 12 respectively, and carrying at its lower end a short, forked rocker, 124, the fork of which straddles a stop or pin, 125, in fixed relation with the main cross-slide 62. These connections are such that at every crosswise movement of the main cross-slide 62 the toggle 117, which is normally struck, is straightened by the movement of the short rocker 124, the links of the toggle moving from either the right or the left to the straight line position according to the direction of movement of the rocker 124. When the toggle is struck by movement of its links in either direction away from its central position the tension device 113 will tension the thread.

The pull-off device *p* is employed for the purpose of performing the function of obtaining an additional amount of lower thread when the work-clamp is vibrated from one stitch-forming position to another on the making of every alternate stitch at either side of the button-hole. The pull-off here employed is of the same general type as that disclosed in Patent #803,876 granted November 28, 1905. That is to say, it is a pull-off operative at every alternate stitch for the purpose of locating the "purl" at the inner edge of the button-hole, to do which it is necessary that the pull-off take place on every outer-edge stitch of the but-

ton-hole in each row of button-hole stitches. In order to do this it is necessary to reverse the timing of the pull-off upon the shifting of the work-clamp for presenting the opposite edge of the button-hole to the stitching mechanism. This reversal of the timing relation or phase of the pull-off is controlled as before indicated, from the shifting mechanism which includes the main cross-slide 62. The connections from this main cross-slide 62 to the lower-thread pull-off may be any suitable for the purpose. Here a depending bracket, 126, is secured to the under side of the plate 12 and has, at its upper and lower ends respectively, vertical bearings for a rock-shaft, 127, carrying at its upper and lower ends respectively two rock arms, 128 and 129, the upper of which is a short forked rocker similar to that shown at 124 and co-operates in a corresponding manner with a pin, 130, secured to the under side of the shifting-bar 99, which, as before pointed out, is connected to the extension 110 of the main cross-slide 62, so that said shifting-bar and cross-slide will move together. At its free end the rock-arm 129 is pivotally connected in turn to the rear end of a rod, 131, the forward end of which is reduced and has a stop, such as the adjustable nut, 132, between which and the shoulder at the opposite end of the reduced portion of the rod two springs, 133 and 134, are intended to work. These springs are separated from each other by the opposite sides of the bored ear (through which the reduced portion of the rod 131 passes) of a rock-rod, 135, extending from and forming in substance a part of a large rock-arm, 136, secured to a short lower rock-shaft 137, the front end of the machine. This rock-shaft is journaled in depending portions, 138 and 139, of the main frame. This rock-shaft, in addition to having the usual turning movement, is also mounted to reciprocate longitudinally of its axis and with it the rock-arm 136, which has a wide forked end adapted to span a rearwardly projecting hub, 140, extending from a large spur-gear, 141, mounted to turn on a stud, 142, secured to the bracket 139. This hub 140 is 115 secured to the bracket 139. This hub 140 is 115 substantially triangular cams disposed oppositely to each other and located at opposite sides of such neutral or circular portion of the hub. These cams are indicated at 143 and 144 respectively. The construction of the parts so far described is such that in the making of a button-hole during the stitching of the first row of short button-hole stitches the forked rock-arm 136 will co-operate with the rear triangular cam 144 and will remain upon it and be rocked back and forth by it 130

intermittently once for each two rotations of the looper-shaft 145. The rocking motion of the arm 136 will of course be transmitted to its rock-shaft 137 (then in its extreme rearward position) and by it to a forward rock-arm, 146, slotted at its free end to surround the rear end of a pin, 147, carried by a rocking link, 148, pivoted at its left-hand end to the lower end of a pivoted lower-thread pull-off ¹⁰, the pivot of which is indicated at 151. At its right-hand end the link 148 has pivoted thereto a block, 148', movable in a slot curved on an arc struck from the pivot of connection of the link and said thread pull-off, the link itself being movable in a slot in its own plane, both of these slots, which are designated respectively by 153 and 154, being formed in a slotted rock-arm, 152, secured to the long rock-shaft 74 operated by ¹⁵ the eccentric-rod 23 from the main upper drive-shaft 21. By these connections the link 148 will be oscillated from the rock-arm 146, the block 148' will travel back and forth in the arc shaped slot, 153, and the lower-thread pull-off will be operated in a manner controlled by the conjoint action of the two rock-shafts 137 and 74, that is to say, said pull-off at every alternate stitch-forming operation is shifted by the rocking ²⁰ of the shaft 137 to a position for drawing off the additional amount of lower thread heretofore referred to. The rock-arm 136 remains upon the cam 144 throughout the making of the first row of button-hole ²⁵ stitches and throughout the making of the first set of barring stitches at the rear end of the button-hole, and upon the rising of the pivot 69 of the shifting lever 60 to shorten the stroke of said lever said rock-arm 136, which is gradually shifted forward during the making of the barring stitches, leaves the cam 144 and travels upon the neutral or circular portion 140 of the hub, against which it is moved by the action of a ³⁰ spring 155 which normally turns the rock-shaft 137 to the left. Immediately thereafter, on the shifting of the main cross-slide 62 into position for forming the second row of button-hole stitches, the mechanism controlling the longitudinal movement of the rock-shaft 137 is operated by said slide and shifts the rock-arm 136 quickly on to the opposite triangular cam 143, the rock-shaft 137 with its arm 146 moving forward at this ³⁵ time. This action results in reversing the timing relation of the pull-off action for the lower thread to assure the formation of the pull at the inner edge of the succeeding row of short button-hole stitches. In this shifted position of the rock-arm 136 the spring 134 is put under tension and serves to hold the parts just described in their forward position, while when in the opposite position the tension on the spring 134 is released and ⁴⁰ tension put upon the spring 133 to hold said

parts in their rearward position, *i. e.* tension is put upon one spring and released from the other in one condition of the parts and is put upon the second spring and released from the first in the opposite condition of ⁴⁵ the parts.

The spur-gear 141 which controls the movements of the triangular cams and forked rock-arm just described is driven, in this case, from the looper-shaft 145 by a ⁵⁰ spur-pinion, 156, in constant mesh therewith. Said looper-shaft in turn is driven from the main upper drive-shaft through sprocket-wheel and chain connections, indicated at 157, 158 and 159. The lower ⁵⁵ sprocket-wheel 159 is carried near the extreme rear end of a short shaft, 160, journaled in the lower rear main bearing, 161, and carrying at its forward end a slotted rock-arm, 162, in the slot of which works ⁶⁰ a crank-pin 163, carried by a crank-arm, 164, secured to said looper-shaft, which shaft has its axis at some distance below the main lower drive-shaft 160. This construction of course is for the purpose of obtaining the ⁶⁵ desired variable rotary movement of the looper-shaft and hence of the looper itself, as will be obvious.

On the completion of a button-hole, consisting of two longitudinal rows of short ⁷⁰ or button-hole stitches and two transverse sets of long barring stitches at the ends of the button-hole, it is customary to complete the button-hole by cutting the fabric between the lines of stitching. For this purpose a cutter and cutter-bar are employed ⁷⁵ which are operated in proper timing with the other mechanism. The button-hole-cutting means employed here is quite similar to that disclosed in my aforesaid patents. The ⁸⁰ cutter proper is indicated at 165 and is of well-known construction. It is shown as carried at the forward end of a cutter-bar made up of two main parts both of which are movable in unison about a vertical axis ⁸⁵ 110 and one of which is movable relatively to the other about a horizontal axis. These two portions of the cutter-bar are designated respectively by 166 and 167, the vertical pivot of the two being indicated at 168 and being ⁹⁰ 115 carried by the plate 12, while the horizontal pivot is indicated at 169, it being a pivot-pin passing through two pairs of depending lugs integral respectively with the two parts ⁹⁵ 166 and 167 of the cutter-bar. A spring 170 ¹²⁰ secured to a lateral extension of the rear end of the forward portion 167 of the cutter-bar and to a fixed point on the frame-work serves to swing the cutter-bar as a whole about its vertical axis 168 to keep the rear ¹⁰⁰ 125 end of the arm 166 in proper relation with a cam formed upon the crank-disk 18, and also serves to rock the forward arm 167 of the cutter-bar about its horizontal axis, when said bar proper is depressed at its for- ¹⁰⁵ 130

ward end, to return the bar proper to its normal position and maintain it therein. At its forward end the cutter-bar proper 167 is shown as having a finger, 171, so shaped 5 as to fit into a notch, 172, in the right-hand side of a block, 173, secured to the lower end of the needle-bar, 174, carrying the needle *n*. The construction is such that at the proper point in the operation of the machine 10 the finger 171 will swing toward the left-hand side of the machine into the notch 172 as the needle-bar is descending and will be locked in said notch and carried down with the needle-bar to force the knife 165 through 15 the opening 5 to cut the opening in the button-hole. At its rear end the arm 166 has a finger, 175, which rides on the periphery of a cam, 176, formed at the upper side of the crank-disk 18. The periphery of this 20 cam is circular throughout the major portion of its length, the periphery being cut away to form a quick let-off face, 177, and a gradual rise, 178, these two cam-faces forming between them a cam-notch covering an 25 arc of about one-sixth of a circle. The function of this cam is to permit the rear end 175 of the cutter-bar to swing into the notch and the forward end 171 to swing into the notch 172 in the needle-bar. Normally 30 this movement is prevented by a latch device, 179, of angular form having a latch, 180, proper adapted to engage an angular detent, 181, on the under side of the cutter-bar near the rear end thereof, and hold said 35 bar with its forward end out of the path of the needle-bar, as shown in Fig. 2. At its rear end the latch device 179, which is normally pressed into engagement with the detent 181 by a spring 182, has a releasing 40 finger, 183, adapted to be engaged and operated by a trip-finger, 184, movable in unison with the crank-disk and with the releasing cam just described. This finger 184, may be adjustable as shown. At the proper 45 point in the operation of the machine, to wit, a short distance in advance of the automatic stopping of the machine, the trip-finger 184 moves the releasing finger 183 to the left of the machine to release the latch 50 proper 180 from the detent 181, whereupon the forward end of the cutter-bar will be swung into the notch 172 as before stated. The tripping of the latch 179 takes place 55 almost immediately after the rear end of the cutter-bar has dropped into the cam notch formed by the faces 177 and 178. After the finger 175 drops off the cam face 177 the cutter-bar is prevented from swinging into the notch in the needle-bar prematurely by 60 means of a stop, 185, which in this case is carried by the secondary slide 63. This stop 185 in the present case is formed on a swinging plate pivoted at 186 on said slide and having a screw-and-slot adjustment, as indicated at 187, for obtaining a fine adjust- 65

ment of the position of said stop 185. This stop moving crosswise with the slide 63, at the proper point, that is, subsequent to the cutting action, serves to swing the rear end of the cutter-bar to the left to cause the re-engagement of the detent 181 by the latch device 179 and the consequent latching of the cutter-bar out of operative relation with the needle-bar.

On the completion of all of the operations of forming the two sets of shorter button-hole stitches and the two sets of long or barring stitches, and the severing of the goods by the knife, the machine is intended to be automatically stopped at the proper point. In many respects the automatic stop mechanism employed for the purpose is preferably similar to that disclosed in a companion application of mine filed March 2, 1912, Serial No. 681,208, in which there is illustrated means for clamping the fast pulley of the machine between a ring surrounding the loose pulley and an extension of the starting lever. Here the fast and loose pulleys are indicated at 188 and 189, the ring surrounding the loose pulley by 190 and the starting lever by 191. The starting lever when swung forward about its pivot, 193, forces the loose pulley into firm engagement with the fast pulley. The starting lever 191 is substantially L-shaped with a forward upward extension, 194, having a friction member, 195, adapted to coact with a gradually rising cam-face, 196, on the face of the pulley 188. By suitable connections the ring 190 and the upward extension 194 of the starting lever are simultaneously moved in opposite directions, these connections comprising a toggle, 197, connected with the lower end of the starting lever, and with a fixed point on the main frame, which toggle is connected by a link, 198, with a rock-shaft, 199, having a fixed rock-arm, or trip-dog 200, and a loose rocker, 201, adapted to be connected to a pedal for resetting 110 the automatic stop mechanism in the position shown in Fig. 1 after it has operated. Said connections also embody a link, 202, connecting the lower end of the ring 190 to suitable means (including an eccentric, not shown) for swinging the lower end of said ring 190 backward or forward in a direction opposite to the movement of the extension 194 of the starting lever. Through these parts, when the loose rocker 201 is operated 115 to strike the toggle 197, the pulleys are coupled and the brake released by the withdrawal of the ring 190 and the extension 194 from the wheel 188, whereas when the machine is to be automatically stopped, a 120 spring, 203, serves to straighten the toggle and force the parts 190 and 194 into engagement with the pulley 188 while at the same time releasing the pulley 189 from the pulley 188. The advantage of this automatic 125 130

stopping means, as pointed out in the aforesaid application, is that a very positive stopping of the mechanism at the desired point in the cycle of operations may be obtained.

- 5 The stop mechanism just described may of course be automatically operated to apply the brake to stop the machine at any desired point in the cycle of operations. In a button-sewing machine the stopping point bears 10 a predetermined relation to the number of stitches used for sewing on a button. This is not true, however, in a button-hole machine in which the number of stitches may be varied within quite wide limits, accord- 15 ing to the length of the hole or the quality of the button-hole stitch, which is determined by the number of stitches taken to a hole of a given length. In order to avoid the necessity of accurately adjusting the 20 stop motion for every adjustment of the machine for button-holes of different sizes, or quality, or both, I provide means for timing the automatic stopping of the machine at a fixed point in the cycle of operations, re- 25 gardless of changes in the adjustment of the button-hole sewing mechanism proper hereinbefore described. Any suitable means may be employed for this purpose. In the preferred construction the means used is such 30 as to assure the automatic stopping of the machine substantially at a predetermined point in the operation of the brake before described, notwithstanding the fact that there is in the present machine no fixed re- 35 lation between the driving wheel and the main controlling device to bring about the operation of the automatic stopping mechanism. Here two separate devices are preferably employed for controlling the release 40 of the automatic stopping mechanism each of which is shown as a trip-lever coöperative with the rock-arm 200. One of these trip-levers is indicated at 204 and the other at 205. These trip-levers, as shown, 45 have a common pivot, 206 about which they turn independently, and the two are quite similar at the rear of said pivot, being in fact substantially identical in construction at their rear ends, each hav- 50 ing a hook or latch, such as 207, and 208, adapted to engage the hooked end of the rock-arm or trip-dog 200. At their forward ends the trip-levers differ in construction, one having a relatively long arm and the 55 other a relatively short arm and one being controlled by a cam that releases it once during each complete cycle of operations, viz., substantially at the end of the cycle, while the other is operated once for every 60 second operation of the needle.

In the present construction the main or short trip-lever 204 is adapted to be engaged at its rear end by a short slide, 209, mounted to move back and forth on the plate 12 sub- 65 stantially in line with the center of rotation

of the crank-disk 18, and having a depending finger, 210, at the under side of said plate, which finger projects into the path of a releasing device, 211, pivoted on the under side of said plate 12 and adapted to coöperate with a rotary trip device, 212, secured to the under side of the main rotary controller and located at the proper point in the periphery of the cam 105. The coacting faces of the pivoted and rotary releasing devices 75 211 and 212 are beveled (see Fig. 9) preferably, to permit the pivoted member to be turned gradually about its pivot and to push toward the left of the machine the depending member 210 and the slide 209 to which 80 it is secured. As shown in this view, the pin 210 is cut away to form a straight edge coacting with the back edge of the hooked end of the pivoted releasing device 211. The tripping device 212 is so located as to actuate 85 the hook 211 to shift the slide 209 as before stated after the completion of the making of the four groups of stitches of the button-hole and the cutting of the button-hole opening, the movement of the slide 209 being 90 sufficient to cause the release of the hook 208 from the hooked lower end of the trip-dog 200 at the time stated. As the point at which the short trip-lever is released from 95 the dog 200 does not bear a fixed relation to the movement of the driving wheel it is likely to be operated out of time with the brake on the driving wheel. In order to prevent this the long trip-lever 205 is provided, which lever holds the dog 200 after it 100 has been released by the main trip-lever 204 and does not release said dog until the driving wheel reaches a fixed point in its operation, which fixed point is just in the rear of the cam-face 196 of said driving wheel. By 105 preventing the release of the trip-dog until this point in the rotation of the driving wheel is reached the driving wheel gets the benefit of the brake for approximately two-thirds of the rotation of said wheel.

The long trip-lever 205 is intended to be operated in timing with the lower-thread pull-off, it being actuated in the present case by a cam movable in unison with the gear-wheel 141 that governs the action of the 110 thread pull-off. In the present construction there is on the hub of said gear-wheel, in addition to the parts before described, a cam, 213, which is substantially heart-shaped and controls the operation of a rock-arm 214, secured to a relatively long sleeve, 215, loosely mounted on the long rock-shaft 74, said sleeve having at its rear end an upwardly extending rocking finger, 216, mounted to work back and forth in a vertical slot, 217, 115 in a guide-plate, 218, between which and the upper face of the bed-plate 3 the forward end of the trip-lever 205 is guided. The upper end of the finger 216 is in constant engagement with the forward end of said trip- 120 125 130

lever and a spring, 219, normally serves to move said lever and the finger 216 to the left (see Fig. 2). At the proper point in the rotation of the gear 141 the heart cam 213 5 raises the free end of the rock-arm 214 sufficiently to rock the sleeve 215 and the finger 216 to a point at which the hook 208 will also be released from the depending rock-arm or trip-dog 200, whereupon the power of the 10 spring 203 will cause the immediate straightening of the toggle 197, the uncoupling of the driving wheel and the application of the brake in such a manner that the machine will always be brought to a stop with the 15 parts in a predetermined position, to wit, with the take-up in its highest position and with the work-clamp at the same side of the button-hole, whether to the right or to the left. The spring 219 serves in this case to 20 restore all of the parts 205, 216, 215, and 214 to their normal positions. In a similar manner a spring, 220, serves to restore the short trip-lever 204 and the parts coacting therewith, to wit, the slide 209, the pin 210 and 25 the pivoted releasing device 211 to their normal positions after they have been shifted in opposition to the action of said spring by the nose of the rotary tripping device 212.

It will of course be evident that in this 30 machine either a whip or a purl stitch may be made. In making the whip stitch the pull-off device for the lower thread is rendered ineffective in some suitable manner, as, for example, by dropping a latch, 221, 35 into a notch (not shown) in the controlling rock-shaft 137 for the lower thread.

It is desirable to make provision for manually operating the rotary controller in order to move the parts controlled thereby without 40 having to turn the fly-wheel of the machine. A suitable device for this purpose is the manual device or lever 222 which co-acts with the forward end of the slide 32 to reciprocate the same and thereby turn the controller and bring about the movement of all 45 the parts operated thereby.

The operation of the mechanism shown herein, constituting the subject matter of the present application is as follows: At the 50 beginning of operations the fast and loose pulleys are of course coupled and the trip-dog 200 latched to the trip-levers 204 and 205, as illustrated in Fig. 1, and these parts of course remain in position for preventing the uncoupling of the pulleys until after the short trip-lever 204 is released from said dog at the end of a cycle of operations of the button-hole-stitch-forming and button-hole-cutting mechanisms. At the beginning 55 of the operation of making a button-hole the work-clamp is in its forward position and at the left-hand side of the button-hole. The main upper drive-shaft 21, being then operated, causes, through the action of the 60 eccentric-rod 22, the oscillation of the rock- shaft 25 and the rock-arm 30 at the upper end thereof, which moves the slide 32 to the right, causing the pawl 41 to bite the walls of the groove 44 in the rotary controller or crank-disk 18 and turn the same 70 one step. On the return of the eccentric-rod to its original position and the withdrawal of the rock-arm 30 from the slide 32 said slide and the dog will be drawn back into position for a new feed movement. 75 Each such step movement of course shifts the connecting-rod 17 and moves the main longitudinal clamp slide 11 one step lengthwise and with it the supported work-clamp to shift the work into position for a new 80 stitch, this action continuing until all of the short stitches at the left-hand side of the button-hole have been made. During this operation the work-clamp is also moved to the right and to the lift intermittently each 85 time the needle rises from the work, this movement resulting in positioning the work properly for the right and left-hand terminal points of each individual stitch. This oscillating movement of the work-clamp crosswise of the machine is brought about through the oscillation of the main shifting lever 60 actuated by the triangular cam 59 through which intermittent oscillation of 90 said shifting lever from the main shaft 21 is obtained; and the pivot 69 of said lever being in its upper position at this time said lever of course has a short stroke at its point of connection with the slide 63 from which slide crosswise movement is directly transmitted to the work-clamp. During these operations of feeding the work-clamp endwise and shifting it crosswise, the needle is operated from the upper shaft in proper timing with said longitudinal and shifting 95 movements and the lower main shaft 145 connected to the looper is also operated in proper timing with the needle, but with the usual variable movement due to the connection illustrated at 160, 162, 163 and 164. 100 During this period at every other operation of the needle the heart-cam 213 will oscillate the long trip-lever 205 through the rock-arm 214, the sleeve 215 and the rocking finger 216; but although at every other operation of said needle the hook 208 will be released from the trip-dog 200 the machine will not be stopped because said dog will still be engaged by the hook 207 of the short trip-lever 204. Simultaneously also with 105 the rotation of said heart-cam the triangular cams 143 and 144 will be rotated and the latter will oscillate the rock-arm 136 back and forth to govern, through the rock-shaft 137, the action of the lower-thread pull-off. 110 As the main rotary controller is turned intermittently the ear 83 on the lever 80 gradually rides up the face of one of the semi-circular cams 84 or 85 and puts the spring 90 under a gradually increasing tension. 115

The rotation of the main controller continues until one of the releasing devices 97 comes into engagement with and trips the latch 92, whereupon the spring 90 instantly shifts the fulcrum-shifting lever 86 to its lowermost position with the fulcrum 69 in position to give the shifting lever 60 its long stroke. Thereupon the work-clamp, through the connections from the shifting-bar 99 hereinbefore described, is oscillated to the position shown in Fig. 12 for the making of the first group of barring stitches. At this time the antifriction roll of the shifting-bar is in the neutral or intermediate cam-groove 107 and the fulcrum 69 being down the shifting lever 60 has its long stroke and gives a correspondingly long crosswise or shifting movement to the work-clamp to make a correspondingly long barring 15 ring stitch, as indicated in said Fig. 12, this stitch having its terminal points located, as will be obvious from said view, substantially at equal distances from the center line of the button-hole to be formed. On the completion of the predetermined number of barring stitches (depending upon the adjustment of the tappets 97 before described) the ear 83 will drop off the high point of the semi-circular cam on which it is at the 25 moment and on to the low point of the other semi-circular cam. This movement is effected by the spring 82, which is also effective to simultaneously turn the fulcrum-shifting lever 86 through the connections before described between the levers 80 and 86 thus causing the restoration of the fulcrum 69 to its upper position in which a relatively short oscillation of the shifting lever 60 is permitted. Thereupon the work-clamp is 35 shifted to the right-hand side of the button-hole, as indicated in Fig. 13, by the riding of the antifriction roller of the shifting-bar 99 into the cam-groove 108, which sets the work-clamp in position for oscillation in a path back and forth crosswise of the machine for making the second or right-hand row of short button-hole stitches. At substantially the same time the tension device 113 is applied again by the striking of the 45 toggle 117, which was straightened at the beginning of the making of the barring stitches. At the same time that the tension is released, as just described, the rock-arm 136 is shifted from the neutral point of the hub between the cams 143 and 144 onto the cam 143. Thereupon the longitudinal movement of the work-clamp in the opposite direction, that is, toward the rear of the machine, begins and continues substantially as 55 before described and at the same time the transverse oscillation or shifting of said work-clamp between the terminal points of stitches to be made at the right-hand side of the button-hole begins, this shifting 60 movement also continuing throughout the

making of the right-hand row of button-hole stitches the fulcrum of the shifting lever 60 is changed again to the lowermost position and the antifriction roll of the shifting-bar 99 rides into the neutral or intermediate cam-groove 109, whereupon the work-clamp is oscillated again a longer distance crosswise of the machine for the making of the second set of barring stitches, as indicated in Fig. 10. All of these operations just described are similar to those previously described in connection with the making of the first row of short stitches and the first set of long barring stitches, the second of the two releasing devices 97 operating however, in this instance to trip the latch 92 prior to the riding of the ear 83 of the lever 80 off the high point of the second of the semi-circular cams. Of course immediately on the shifting of the work-clamp, by the movement of the shifting-bar 99 into the cam-groove 109, the tension device and the rock-shaft connected with the rock-arm 136 are operated again, said rock-arm being shifted first to the neutral or central position on the round part of the hub, where it will remain until the completion of the second set of barring stitches, whereupon the fulcrum 69 will rise again and immediately thereafter the rock arm 136 will shift back on to the other triangular cam 144, the tension device being also shifted again at the same time. At the proper point in the movement of the main rotary controlling devices the cutter-bar is tripped by the release of the latch 179 by the finger 184 and the forward end of said bar locks into the notch in the needle-bar and is carried down with said bar and operated to cut the button-hole substantially as set forth in my aforesaid patents. Shortly thereafter, on the rising of the cutter-bar, it is latched again out of operative position by the latch device 179, and when the trip device 212 oscillates the pivoted trip 211 the short trip-lever is released from the stop mechanism. The rotation of the main drive-shaft continues, however, until at the proper point in the rear of the brake (before described) the long trip-lever 205 is released in proper timing with the action of the stitch-forming mechanism, whereupon the dog 200 is released and the brake automatically applied to stop the machine.

What I claim is:—

1. In a button-hole sewing machine, the combination with a main driver, of stitch-forming means operated thereby for stitching a button-hole, a work-clamp, a controller having an adjustable rotary movement and being rotatable once for each cycle of button-hole-forming operations, automatic stopping means for the main driver and a pair of separately operative trip-levers coöperative for releasing said automatic

- stopping means, one of said trip-levers being operable by said controller at a predetermined point in the rotation thereof and the other being operable by the main driver at 5 a predetermined point in its rotation.
2. In a button-hole sewing machine, the combination with a main driver, of stitch-forming means operated thereby for stitching a button-hole, a work-clamp, a controller having an adjustable rotary movement and being rotatable once for each cycle of button-hole-forming operations, automatic stopping means for the main driver, and a pair of trip devices for releasing said 10 15 20 25 30 35 40 45 50 55 60 65 70 75 80 85 90 95 100 105 110 115 120 125 130
- automatic stopping means said devices being successively effective in the order named, viz.—a trip device operable by said controller at a predetermined point in the rotation thereof, and a trip device operable by the main driver at a predetermined point in its rotation.
3. In a button-hole sewing machine, the combination with a main driver, of stitch-forming means operated thereby for stitching a button-hole, a work-clamp, a controller having an adjustable rotary movement and being rotatable once for each cycle of button-hole-forming operations, automatic stopping means for the main driver and including a rotary brake member movable in timing with said driver, and a pair of trip devices for releasing said automatic stopping means said devices being successively effective in the order named, viz.—a trip device operable by said controller at a predetermined point in the rotation thereof, and a trip device operable by the main driver at a predetermined point in the rotation of said brake member.
4. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a rotary controller governed by said main driver and rotatable once for each cycle of button-hole-forming operations, means governed by said rotary controller for moving said work-clamp in said respective paths, and means carried by said controller for varying the length of time that the work-clamp is moved in said barring path.
5. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said cloth-clamp is connected, and a shifting lever governed by said main driver for oper- ating said cross-slide and having a fulcrum shiftable for controlling the shifting movements of the work-clamp.
6. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitching, a cross-slide to which said work-clamp is connected, a shifting lever governed by said main driver for operating said cross-slide and having a shiftable fulcrum, and automatic means for shifting said fulcrum to positions for controlling the making of either short stitches or barring stitches.
7. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a rotary controller governed by said main driver and rotatable once for each cycle of button-hole-forming operations, means governed by said rotary controller for moving said cross-slide to positions corresponding to the lengths of said stitches, and means carried by said rotary controller for varying the length of time that the work-clamp is moved in said barring path.
8. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a rotary controller governed by said main driver and rotatable once for each cycle of button-hole-forming operations, means governed by said rotary controller for moving said cross-slide to positions corresponding to the lengths of said stitches, and adjustable means carried by said rotary controller for varying the length of time that the work-clamp is moved in said barring path.
9. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a rotary controller governed by said main driver and rotatable once for each cycle of button-hole-forming

operations, means governed by said rotary controller for moving said cross-slide to positions corresponding to the lengths of said stitches, and means carried by said rotary controller for varying twice during each cycle of button-hole-forming operations the length of time that the work-clamp is moved in said barring path.

10. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a shifting member governed by said main driver for operating said work-clamp, a rotary controller governed by said main driver and rotatable once for each cycle of button-hole-forming operations, and means including two pairs of controlling elements carried by said rotary controller for changing the stroke of said shifting member four times during each rotation of said controller.

11. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a shifting member governed by said main driver for operating said cloth-clamp, a rotary controller governed by said main driver and rotatable once for each cycle of button-hole-forming operations, and means including a pair of let-off cams and a pair of tripping devices all carried by said rotary controller for changing the stroke of said shifting member four times during each rotation of said controller.

12. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a shifting member governed by said main driver for operating said work-clamp, a rotary controller governed by said main driver and rotatable once for each cycle of button-hole-forming operations, and means governed by said rotary controller for changing the stroke of said shifting member said means including a pair of adjustable members carried by said rotary controller for changing to the long stroke of said shifting member.

13. In a button-hole sewing machine, the combination with a main driver, of stitch-

forming means operated thereby for stitching a button-hole, a work-clamp shiftable crosswise of the machine through paths of different lengths corresponding respectively to short button-hole stitches and long barring stitches, a cross-slide to which said work-clamp is connected, a shifting lever mounted on said cross-slide for actuating the work-clamp and having a shiftable fulcrum, a rotary controller governed by said main driver and rotatable once for each cycle of button-hole-forming operations, and means governed by said rotary controller for moving said cross-slide to positions corresponding to the lengths of the stitches and for also shifting the fulcrum of said shifting lever to change the stroke of the work-clamp.

14. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a cross-slide to which said work-clamp is connected, a shifting lever operated by the main driver and mounted on said cross-slide for actuating the work-clamp and having a shiftable fulcrum, a rotary controller governed by said main driver and rotatable once for each cycle of button-hole-forming operations, and means governed by said rotary controller for moving said cross-slide to positions corresponding to the lengths of the stitches and for also shifting the fulcrum of said shifting lever to change the stroke of the work-clamp.

15. In a button-hole sewing machine, the combination with a main driver, of stitch-forming means operated thereby for stitching a button-hole, a work-clamp shiftable crosswise of the machine through paths of different lengths corresponding respectively to short button-hole stitches and long barring stitches, a combined rotary cam and step-by-step wheel operated by said main driver and rotatable once for each cycle of button-hole-forming operations and having a cam-face encircling the axis of rotation of the wheel and comprising four segments disposed at different distances from said axis corresponding to crosswise positions of the work-clamp, means operated by the cam for shifting the work-clamp to said positions, and a connecting-rod pivoted to said wheel substantially in the diameter passing through the centers of the barring portions of said cam and also connected with said work-clamp for actuating the same back and forth step-by-step.

16. In a button-hole sewing machine, the combination with a main driver, of stitch-forming means operated thereby, a work-clamp, a rotary controller rotatable from said main driver once for each cycle of but-

ton-hole-forming operations, and the following instrumentalities governed by said rotary controller viz.—means for feeding the work-clamp step-by-step, a main cross-slide for shifting the position of the work-clamp, an auxiliary cross-slide carried by and movable relatively to said main cross-slide, and a shifting member secured to said auxiliary cross-slide for moving the work-clamp crosswise in any of said positions.

17. In a button-hole sewing machine, the combination with a main driver, of stitch-forming means operated thereby, a work-clamp, a rotary controller rotatable from said main driver once for each cycle of button-hole-forming operations, and the following instrumentalities governed by said rotary controller viz.—means for feeding the work-clamp step-by-step, a cross-slide for shifting the position of the work-clamp, and a shifting lever carried by said cross-slide for moving the work-clamp crosswise in any of said positions.

18. In a button-hole sewing machine, the combination with a main driver, of stitch-forming means operated thereby, a work-clamp, a rotary controller rotatable from said main driver once for each cycle of button-hole-forming operations, and the following instrumentalities governed by said rotary controller viz.—means for feeding the work-clamp step-by-step, a main cross-slide for shifting the position of the work-clamp, an auxiliary cross-slide carried by and movable relatively to said main cross-slide, and a shifting lever pivoted on said auxiliary cross-slide for moving the work-clamp crosswise in any of said positions.

19. In a button-hole sewing machine, the combination with a main driver, of stitch-forming means operated thereby, a work-clamp, a rotary controller rotatable from said main driver once for each cycle of button-hole-forming operations, a cam on the main driver, and the following instrumentalities governed by said rotary controller viz.—a main cross-slide for shifting the position of the work-clamp an auxiliary cross-slide carried by and movable relatively to the main cross-slide, and a shifting member secured to said auxiliary cross-slide and operated by said cam for moving the work-clamp and said auxiliary cross-slide crosswise relatively to the main cross-slide.

20. In a button-hole sewing machine, the combination with a main driver, of stitch-forming means operated thereby, a work-clamp, a rotary controller rotatable from said main driver once for each cycle of button-hole-forming operations, a cam on the main driver, and the following instrumentalities governed by said rotary controller viz.—a main cross-slide for shifting the position of the work-clamp, an auxiliary cross-slide carried by and movable relatively to

the main cross-slide, and a shifting lever pivoted on said auxiliary cross-slide and operated by said cam for moving the work-clamp and the auxiliary cross-slide crosswise relatively to the main cross-slide.

21. In a button-hole sewing machine, the combination with a main driver, of stitch-forming means operated thereby, a work-clamp, a rotary controller rotatable from said main driver once for each cycle of button-hole-forming operations, a triangular cam on the main driver, and the following instrumentalities governed by said rotary controller viz.—a main cross-slide for shifting the position of the work-clamp, an auxiliary cross-slide carried by and movable relatively to the main cross-slide, and a shifting lever pivoted on said auxiliary cross-slide and operated intermittently by said cam twice during each rotation of the main driver for moving the work-clamp and said auxiliary cross-slide crosswise relatively to the main cross-slide.

22. In a button-hole sewing machine, the combination with a main driver, of stitch-forming means operated thereby, a work-clamp, a rotary controller rotatable from said main driver once for each cycle of button-hole-forming operations, and the following instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp crosswise in any of said positions, and fulcrum-shifting means movable in unison with said rotary controller for changing the fulcrum of said shifting lever.

23. In a button-hole sewing machine, the combination with a main driver, of stitch-forming means operated thereby, a work-clamp, a rotary controller rotatable from said main driver once for each cycle of button-hole forming operations, and the following instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp crosswise in any of said positions, and fulcrum-shifting means movable in unison with said rotary controller for changing the fulcrum of said shifting lever, said means embodying a pair of oppositely disposed trip devices.

24. In a button-hole sewing machine, the combination with a main driver, of stitch-forming means operated thereby, a work-clamp, a rotary controller rotatable from

- said main driver once for each cycle of button-hole-forming operations, and the following instrumentalities governed by said rotary controller viz.—means for feeding the 5 work-clamp step by step, a main cross-slide for shifting the position of the work-clamp, an auxiliary cross-slide carried by and movable relatively to said main cross-slide, a shifting lever pivoted on said auxiliary 10 cross-slide for moving the work-clamp cross-wise in any of said positions, and fulcrum-shifting means for changing the fulcrum of said shifting lever, said means embodying a pair of controlling devices movable in unison with the rotary controller and one governing the shifting of said fulcrum in one direction and the other the shifting of said fulcrum in another direction.
25. In a button-hole sewing machine, the 20 combination with a main driver, of stitch-forming means operated thereby, a work-clamp, a rotary controller rotatable from said main driver once for each cycle of button-hole-forming operations, and the following 25 instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp 30 crosswise in any of said positions, and fulcrum-shifting means for changing the fulcrum of said shifting lever, said means embodying a pair of oppositely disposed trip devices movable in unison with the rotary controller and governing the shifting of said fulcrum to the long stroke of the shifting lever twice during each rotation of said controller and also embodying a pair of oppositely disposed cams, also movable in unison 35 with said controller and governing the shifting of said fulcrum to the short stroke of the shifting lever twice during each such rotation.
28. In a button-hole sewing machine, the 40 combination with a main driver, of stitch-forming means operated thereby, a work-clamp, a rotary controller rotatable from said main driver once for each cycle of button-hole-forming operations, and the following 45 instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp cross-wise in any of said positions, and fulcrum-shifting means movable in unison with said 50 rotary controller for changing the fulcrum of said shifting lever said means embodying a pair of oppositely disposed cams.
29. In a button-hole sewing machine, the 55 combination with a main driver, of stitch-forming means operated thereby, a work-clamp, a rotary controller rotatable from said main driver once for each cycle of button-hole-forming operations, and the following 60 instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp cross-wise in any of said positions, and fulcrum-
- and governing the shifting of said fulcrum 65 to the short stroke of the shifting lever.
27. In a button-hole sewing machine, the combination with a main driver, of stitch-forming means operated thereby, a work-clamp, a rotary controller rotatable from 70 said main driver once for each cycle of button-hole-forming operations, and the following instrumentalities governed by said rotary controller viz.—means for feeding the work-clamp step-by-step, a main cross-slide for shifting the position of the work-clamp, an auxiliary cross-slide carried by and movable relatively to said main cross-slide, a shifting lever pivoted on said auxiliary cross-slide for moving the work-clamp 75 crosswise in any of said positions, and fulcrum-shifting means for changing the fulcrum of said shifting lever, said means embodying a pair of oppositely disposed trip devices movable in unison with the rotary controller and governing the shifting of said fulcrum to the long stroke of the shifting lever twice during each rotation of said controller and also embodying a pair of oppositely disposed cams, also movable in unison 80 with said controller and governing the shifting of said fulcrum to the short stroke of the shifting lever twice during each such rotation.
28. In a button-hole sewing machine, the 85 combination with a main driver, of stitch-forming means operated thereby, a work-clamp, a rotary controller rotatable from said main driver once for each cycle of button-hole-forming operations, and the following 90 instrumentalities governed by said rotary controller viz.—means for feeding the work-clamp to the long stroke of the shifting lever twice during each rotation of said controller and also embodying a pair of oppositely disposed cams, also movable in unison with said controller and governing the shifting of said fulcrum to the short stroke of the shifting lever twice during each such rotation.
28. In a button-hole sewing machine, the 95 combination with a main driver, of stitch-forming means operated thereby, a work-clamp, a rotary controller rotatable from said main driver once for each cycle of button-hole-forming operations, and the following 100 instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp cross-wise in any of said positions, and fulcrum-shifting means movable in unison with said 105 rotary controller for changing the fulcrum of said shifting lever said means embodying a pair of oppositely disposed cams.
29. In a button-hole sewing machine, the 110 combination with a main driver, of stitch-forming means operated thereby, a work-clamp, a rotary controller rotatable from said main driver once for each cycle of button-hole-forming operations, and the following 115 instrumentalities governed by said rotary controller viz.—means for feeding the work-clamp step by step, a main cross-slide for shifting the position of the work-clamp, an auxiliary cross-slide carried by and movable relatively to said main cross-slide, a shifting lever pivoted on said auxiliary cross-slide for moving the work-clamp cross-wise in any of said positions, and fulcrum-
- and governing the shifting of said fulcrum 120 to the short stroke of the shifting lever.
27. In a button-hole sewing machine, the combination with a main driver, of stitch-forming means operated thereby, a work-clamp, a rotary controller rotatable from 125 said main driver once for each cycle of button-hole-forming operations, and the following instrumentalities governed by said rotary controller viz.—means for feeding the work-clamp step-by-step, a main cross-slide for shifting the position of the work-clamp, an auxiliary cross-slide carried by and movable relatively to said main cross-slide, a shifting lever pivoted on said auxiliary cross-slide for moving the work-clamp cross-wise in any of said positions, and fulcrum-

shifting means movable in unison with said rotary controller for changing the fulcrum of said shifting lever said means embodying a pair of oppositely disposed substantially 5 semicircular cams.

30. In a button-hole sewing machine, the combination with a main driver, of stitch-forming means operated thereby, a work-clamp, a rotary controller rotatable from 10 said main driver once for each cycle of button-hole-forming operations, and the following instrumentalities governed by said rotary controller viz.—means for feeding the work-clamp step by step, a main cross-slide 15 for shifting the position of the work-clamp, an auxiliary cross-slide carried by and movable relatively to said main cross-slide, a shifting lever pivoted on said auxiliary cross-slide for moving the work-clamp cross- 20 wise in any of said positions, and fulcrum-shifting means for changing the fulcrum of said shifting lever, said means embodying a pair of separate actuators governed by separate controlling devices movable in unison 25 with said rotary controller, one of said actuators controlling the short stroke and the other the long stroke of said shifting lever.

31. In a button-hole sewing machine, the combination with a main driver, of stitch-forming means operated thereby, a work-clamp, a rotary controller rotatable from 30 said main driver once for each cycle of button-hole-forming operations, and the following instrumentalities governed by said rotary controller viz.—means for feeding the work-clamp step-by-step, a main cross-slide 35 for shifting the position of the work-clamp, an auxiliary cross-slide carried by and movable relatively to said main cross-slide, a shifting lever pivoted on said auxiliary cross-slide for moving the work-clamp cross- 40 wise in any of said positions, and fulcrum-shifting means for changing the fulcrum of said shifting lever, said means embodying a 45 pair of separate actuators one governing the short and the other the long stroke of said shifting lever and also embodying two pairs of controlling devices movable in unison with said rotary controller.

50. 32. In a button-hole sewing machine, the combination with a main driver, of stitch-forming means operated thereby, a work-clamp, a rotary controller rotatable from 55 said main driver once for each cycle of button-hole-forming operations, and the following instrumentalities governed by said rotary controller viz.—means for feeding the work-clamp step-by-step, a main cross-slide 60 for shifting the position of the work-clamp, an auxiliary cross-slide carried by and movable, relatively to said main cross-slide, a shifting lever pivoted on said auxiliary cross-slide for moving the work-clamp cross- 65

shifting means for changing the fulcrum of 65 said shifting lever, said means embodying a pair of spring-pressed levers operatively connected with said shifting lever and one controlling the short and the other the long stroke of said shifting lever, said fulcrum-shifting means also embodying separate controlling devices movable in unison with the rotary controller. 70

33. In a button-hole sewing machine, the combination with a main driver, of stitch-forming means operated thereby, a work-clamp, a rotary controller rotatable from 75 said main driver once for each cycle of button-hole-forming operations, and the following instrumentalities governed by said rotary controller viz.—means for feeding the work-clamp step by step, shifting mechanism for the work-clamp, a lower-thread pull-off, and controlling devices movable in 80 unison with said rotary controller for governing the feed movements of the work-clamp, the shifting movements of said shifting mechanism and the operation of said lower-thread pull-off. 85

34. In a button-hole sewing machine, the combination with a main driver, of stitch-forming means operated thereby, a work-clamp, a rotary controller rotatable from 90 said main driver once for each cycle of button-hole-forming operations, and the following instrumentalities governed by said rotary controller viz.—means for feeding the work-clamp step by step, shifting mechanism for the work-clamp, a lower-thread pull-off, a tension device, and controlling devices 95 movable in unison with said rotary controller for governing the feed movements of the work-clamp, the shifting movements of said shifting mechanism and the operations of said lower-thread pull-off and the tension device. 100

35. In a button-hole sewing machine, the combination with a main driver, of stitch-forming means operated thereby, a work-clamp, a rotary controller rotatable from 110 said main driver once for each cycle of button-hole forming operations, and the following instrumentalities governed by said rotary controller viz.—means for feeding the work-clamp step by step, shifting mechanism for the work-clamp, a lower-thread pull-off, a tension device, a button-hole cutting device, and controlling devices movable in unison with said rotary controller for governing the feed movements of the work-clamp, the shifting movements of said shifting mechanism, the operations of said lower-thread pull-off 115 and the tension device, and the action of said button-hole cutting device. 120

36. In a button-hole sewing machine, the combination with a main driver, of stitch-forming means operated thereby, a work-clamp, a rotary controller rotatable from 125

- 5 said main driver once for each cycle of button-hole-forming operations, and the following instrumentalities governed by said rotary controller viz.—means for feeding the 10 work-clamp step-by-step, shifting mechanism for the work-clamp, a lower-thread pull-off, a tension device, a button-hole-cutting device, automatic stop mechanism, and controlling devices movable in unison with 15 said rotary controller for governing the feed movements of the work-clamp, the shifting movements of said shifting mechanism, the operations of said lower-thread pull-off and the tension device, the action of said button-hole-cutting device, and the throwing of 20 said automatic stop mechanism into action.

37. In a button-hole sewing machine, the combination with a main driver, stitch-forming means operated thereby, a work-clamp, and shifting mechanism for the work-clamp, of a rotary controller rotatable once for 25 each cycle of button-hole-forming operations and embodying the following instrumentalities viz.—a feed connection for feeding said work-clamp, a pair of releasing devices disposed in different circumferential positions but adjacent to each other for controlling dissimilar shifting movements of 30 said shifting mechanism, said releasing devices being adjustable circumferentially relatively to each other, and means including a cam encircling the axis of said rotary controller for effecting said shifting movements.

35 38. In a button-hole sewing machine, the combination with a main driver, stitch-forming means operated thereby, a work-clamp, and shifting mechanism for the work-clamp, of a rotary controller rotatable once for each cycle of button-hole forming 40 operations and embodying the following instrumentalities viz.—a feed connection for feeding said work-clamp, two pairs of diametrically opposite releasing devices the 45 devices of one of which pairs are disposed in different circumferential positions from those of the other pair and control different shifting movements of said shifting mechanism, and a cam for effecting said shifting 50 movements.

39. In a button-hole sewing machine, the combination with a main driver, stitch-forming means operated thereby, a work-clamp, and shifting mechanism for the 55 work-clamp, of a rotary controller rotatable once for each cycle of button-hole forming operations and embodying the following instrumentalities viz.—a feed connection for feeding said work-clamp, a pair of diametrically opposite trip devices controlling one 60 shifting movement of said shifting mechanism, a pair of diametrically opposite cams having let-off points disposed in different circumferential positions from said trip devices for controlling another shifting movement of 65 said shifting mechanism, and a cam for effecting said shifting movements and controlling said tension device and also controlling the lower-thread of the 70 machine, and a trip device controlling the automatic stopping of the machine.

40. In a button-hole sewing machine, the combination with a main driver, stitch-forming means operated thereby, a work-clamp, and shifting mechanism for the work-clamp, of a rotary controller rotatable once for each cycle of button-hole forming 75 operations and embodying the following instrumentalities viz.—a feed connection for feeding said work-clamp, a pair of diametrically opposite trip devices controlling one shifting movement of said shifting mechanism, a pair of diametrically opposite cams having let-off points disposed in different circumferential positions from said trip devices for controlling another shifting movement of said shifting mechanism, a cam for effecting said shifting movements, and a trip device controlling the automatic stopping of 80 the machine.

41. In a button-hole sewing machine, the combination with a main driver, stitch-forming means operated thereby, a work-clamp, and shifting mechanism for the work-clamp, of a rotary controller rotatable once for each cycle of button-hole forming 85 operations and embodying the following instrumentalities viz.—a feed connection for feeding said work-clamp, a pair of diametrically opposite trip devices controlling one shifting movement of said shifting mechanism, a pair of diametrically opposite cams having let-off points disposed in different circumferential positions from said trip devices for controlling another shifting movement of said shifting mechanism, a cam for effecting said shifting movements, a cam-notch for controlling the cutting of the button-hole, and a trip device controlling the 90 automatic stopping of the machine.

42. In a button-hole sewing machine, the combination with a main driver, stitch-forming means operated thereby, a work-clamp, a tension device, and shifting mechanism for the work-clamp, of a rotary controller rotatable once for each cycle of button-hole forming 95 operations and embodying the following instrumentalities viz.—a feed connection for feeding said work-clamp, a pair of diametrically opposite trip devices controlling one shifting movement of said shifting mechanism, a pair of diametrically opposite cams having let-off points disposed in different circumferential positions from said trip devices for controlling another shifting movement of said shifting mechanism, a cam for effecting said shifting movements, a cam-notch for controlling the cutting of the button-hole, and a trip device controlling the 100 automatic stopping of the machine.

43. In a button-hole sewing machine, the combination with a main driver, stitch-forming means operated thereby, a work-clamp, a tension device, and shifting mechanism for the work-clamp, of a rotary controller rotatable once for each cycle of button-hole forming 105 operations and embodying the following instrumentalities viz.—a feed connection for feeding said work-clamp, a pair of diametrically opposite trip devices controlling one shifting movement of said shifting mechanism, a pair of diametrically opposite cams having let-off points disposed in different circumferential positions from said trip devices for controlling another shifting movement of said shifting mechanism, a cam for effecting said shifting movements, a cam-notch for controlling the cutting of the button-hole, and a trip device controlling the 110 automatic stopping of the machine.

44. In a button-hole sewing machine, the combination with a main driver, stitch-forming means operated thereby, a work-clamp, a tension device, and shifting mechanism for the work-clamp, of a rotary controller rotatable once for each cycle of button-hole forming 115 operations and embodying the following instrumentalities viz.—a feed connection for feeding said work-clamp, a pair of diametrically opposite trip devices controlling one shifting movement of said shifting mechanism, a pair of diametrically opposite cams having let-off points disposed in different circumferential positions from said trip devices for controlling another shifting movement of said shifting mechanism, a cam for effecting said shifting movements, a cam-notch for controlling the cutting of the button-hole, and a trip device controlling the 120 automatic stopping of the machine.

45. In a button-hole sewing machine, the combination with a main driver, stitch-forming means operated thereby, a work-clamp, a tension device, and shifting mechanism for the work-clamp, of a rotary controller rotatable once for each cycle of button-hole forming 125 operations and embodying the following instrumentalities viz.—a feed connection for feeding said work-clamp, a pair of diametrically opposite trip devices controlling one shifting movement of said shifting mechanism, a pair of diametrically opposite cams having let-off points disposed in different circumferential positions from said trip devices for controlling another shifting movement of said shifting mechanism, a cam for effecting said shifting movements, a cam-notch for controlling the cutting of the button-hole, and a trip device controlling the automatic stopping of the machine.

clamp, shifting mechanism for shifting the work-clamp crosswise, a tension device, and a tension-controlling toggle movable to opposite sides of a central straight position, 5 of a rotary controller rotatable once for each cycle of button-hole forming operations and embodying the following instrumentalities viz.—a feed connection for feeding said work-clamp, releasing devices controlling 10 the shifting movements of said shifting mechanism and toggle, and a cam for effecting said shifting movements.

44. In a button-hole sewing machine, the combination with a main driver, stitch-forming means operated thereby, a work-clamp, shifting mechanism for shifting the work-clamp crosswise, and a lower-thread pull-off, of a rotary controller rotatable once for each cycle of button-hole-forming operations 20 and embodying means for governing said shifting mechanism and the lower-thread pull-off.

45. In a button-hole sewing machine, the combination with a main driver, stitch-forming means operated thereby, a work-clamp, shifting mechanism for shifting the work-clamp crosswise, and a lower-thread pull-off mounted to reciprocate endwise of the machine, of a rotary controller rotatable 30 once for each cycle of button-hole forming operations and embodying means for actuating said shifting mechanism and the lower-thread pull-off.

46. In a button-hole sewing machine, the combination with a main driver, stitch-forming means operated thereby, a work-clamp, shifting mechanism for shifting the work-clamp crosswise, and a lower-thread pull-off mounted to oscillate about an axis 40 and to reciprocate endwise of the machine, of a rotary controller rotatable once for each cycle of button-hole forming operations and embodying means for actuating said shifting mechanism and the lower-thread pull-off.

47. In a button-hole sewing machine, the combination with a main driver, of stitch-forming means operated thereby, a work-clamp, shifting mechanism for shifting the work-clamp crosswise, a tension device, and a tension-controlling toggle connected with 50 said shifting mechanism and movable by it from a central straight position to a struck position at either side thereof.

48. In a button-hole sewing machine, the combination with a main driver, of stitch-forming means operated thereby, a work-clamp, shifting mechanism for shifting the work-clamp crosswise, a tension device, a 60 tension-controlling toggle connected with said shifting mechanism and movable by it

from a central position to a struck position at either side thereof, and a rotary controller rotatable once for each cycle of button-hole-forming operations and governing the crosswise movements of said shifting mechanism. 65

49. In a button-hole sewing machine, the combination with a main driver, of stitch-forming means operated thereby and including a needle-bar, a work-clamp, button-hole cutting mechanism including a cutter-bar carried by the work-clamp and movable into and out of position for operation by the needle-bar, shifting mechanism including 70 a cross-slide for shifting said work-clamp crosswise of the machine and for also moving said cutter-bar out of operative relation with the needle-bar, and a rotary controller operated from the main driver and 75 rotatable once for each cycle of button-hole forming operations and governing the shifting of said cutter-bar into operative relation with the needle-bar and also governing said movements of the shifting mechanism. 80

50. In a button-hole sewing machine, the combination with a main driver, of stitch-forming means operated thereby, a work-clamp, a cross-slide having a vertical guide, 90 a shifting lever operated by the main driver and connected to the work-clamp and having a fulcrum member movable up and down in said guide, a rotary controller rotatable once for each cycle of button-hole forming 95 operations, and means governed by said rotary controller for shifting said fulcrum member up and down in said guide at different points in said cycle.

51. In a button-hole sewing machine, the combination with a main driver, of stitch-forming means operated thereby, a work-clamp, a cross-slide having a vertical guide, a shifting lever operated by the main driver and connected to the work-clamp and having a fulcrum member movable up and down in said guide, a rotary controller rotatable once for each cycle of button-hole forming operations, and means governed by said rotary controller and including a fulcrum-shifting lever connected to the fulcrum member of said shifting lever for shifting said fulcrum member up and down in said guide at different points in said cycle. 105 110

Signed at Cleveland, in the county of Cuyahoga, and State of Ohio, this 16th day of July, A. D. 1913.

GEORGE W. NELSON.
